(57) **CLAIM**

The ornamental designs for a computer display with icons, as shown and described.

DESCRIPTION

FIG. 1 is a front view of a computer display with icons showing the new design in a first embodiment; and, FIG. 2 is a front view of a computer display with icons showing the new design in a second embodiment.

The broken lines shown in the drawings illustrate portions of the computer screen with icons that form no part of the claimed design.

The icon(s) shown in this disclosure constitute a trademark of the assignee company, Vixlet, LLC. The icon(s) shown in this disclosure also constitute material covered by copyright owned by the assignee company. The assignee company, owner of the copyright and trademark, has no objection to the reproduction of the patent document or the patent disclosure, as it appears in the U.S. Patent Office records, but reserves all other copyright and trademark rights whatsoever.
